UNITED STATES PATENT OFFICE.

GEORGE BROWN, OF BOSTON, MASSACHUSETTS.

DESIGN FOR AN END PIECE FOR COUCHES.

SPECIFICATION forming part of Design No. 32,594, dated April 24, 1900.

Application filed October 23, 1899. Serial No. 734,587. Term of patent 31 years.

To all whom it may concern:

Be it known that I, GEORGE BROWN, of Boston, county of Suffolk, and State of Massachusetts, have invented and produced a new 5 and original Design for an End Piece for Couches, of which the following description, in connection with the accompanying drawing, is a specification, like letters on the drawing representing like parts.

10 The drawing is a perspective view of an end piece for couches embodying the design.

The leading feature of the design consists in the general shape and configuration of the end piece, the upper and side edges of said 15 end piece being somewhat curved, as shown at a and a^2 , while the side edges terminate at the base of the couch, where the flat surfaces

b are formed, as shown. The said flat surfaces are narrow, constituting the feet of the couch, and from the inner ends of the said 20 surfaces b the edge of the end piece curves upward, as shown at a^3 , the upcurves rounding inward and meeting in a substantially-horizontal line a^4 .

I claim—

The design for an end piece for couches, substantially as herein shown and described.

In testimony whereof I have signed my name to this specification in the presence of two subscribing witnesses.

GEORGE BROWN.

Witnesses:

HENRY J. LIVERMORE,
NANCY P. FORD.
